(Cl. D54—13)

To all whom it may concern:

Be it known that I, Joseph C. Lutz, a citizen of the United States, residing in Saint Paul, county of Ramsey, and State of Minnesota, have invented a new, original, and ornamental Design for a Tire Lift, for which the following is a specification, reference being had to the accompanying drawings, forming part thereof:

I claim:

The ornamental design for a tire lift, as shown.
JOSEPH C. LUTZ.
